CIRCULAR KNITTING MACHINE

Carlyle Herbert Wainwright, Leicester, England,
assignor to The Bentley Engineering Company
Limited, Leicester, England, a British company
Application June 24, 1941, Serial No. 399,516

In Great Britain July 1, 1940

10 Claims. (Cl. 66—47)

This invention consists of improvements in or relating to circular knitting machines and is particularly concerned with those devices known as "pickers" which are employed in knitting machines to move a needle, or more than one needle, from one position to another in the track or groove in which the needle or each needle is situated. For instance, in the knitting of heel and toe pouches, the necessary narrowing and widening of the knitted fabric is produced by the shifting of one needle or two needles simultaneously from the control of one cam track to the control of another.

One form of such device which is in common use (and on which the present invention constitutes an improvement) consists (in the case of a machine having a moving needle cylinder and a stationary cam-box) of a lever or arm pivoted outside the needle cylinder on a stationary part of the machine or on a bracket attached to a stationary part of the machine. When in its operative position the arm extends more or less radially of the needle cylinder with its inner or free end close to the cylinder within range of the butts of the needle sliders as the sliders move round with the cylinder. The arm is pivoted about a vertical axis and also about a horizontal axis so that the end close to the cylinder can move in any direction on its own sphere, but the direction in which it does move is determined by a cam with which the arm makes contact either at some point between the pivot and the end close to the cylinder or on an extension of the arm on the side of the pivot away from the cylinder. At its free end the arm is formed with a horizontal portion and a vertical wall to engage the slider butts. Assuming the picker is to lower two needles in each direction of each reciprocation of the needle cylinder during the widening operation on a heel or toe pouch, the horizontal portion and vertical portion will take the form of a letter T and the mode of operation will be as follows:

When the butt of the first needle slider to be lowered has reached the picker, it will pass under the horizontal portion and strike against the vertical wall. By this time the next following butt will also be safely under the horizontal portion. Continued movement of the butts will turn the picker about the vertical axis of its pivot and the action of the cam will cause it to turn about the horizontal axis also. The horizontal portion of the end will then come in contact with the upper edges of the butts and will lower the sliders until, owing to the mutually divergent

paths of the picker end and the butts, the butts become out of reach of the pickers. The butts will, by this time, be lowered to a position where they are out of range of the cam track which was previously controlling them.

5 Pickers of the known type described operate satisfactorily up to a point, but butt breakages and miss-picking do occur and they become serious faults at high speeds. Butt breakages have been discovered to be caused most usually by friction between the arm and the cam, making the action hard; and miss-picking has been caused by sluggish return of the arm to its receiving position, also due to friction between the arm and cam. An increase in the strength of the spring which returns the arm to its receiving position, while tending to relieve the latter fault, will only aggravate the former.

15 It is the object of the present invention to overcome both these difficulties.

The present invention comprises, in or for a circular knitting machine, the combination of a picker movable about two axes transverse to one another, means which serves to rock the picker about one axis and which comprises two arms inclined towards one another to embrace the picker, resilient means to permit and to control movement of the picker about the other axis, and means to move the arms for the purpose of rocking the picker. Preferably, the movement imparted to the arms rocks the picker about an axis that will move its operative end (i. e. the end which will engage a needle slider or a needle) lengthwise of the needles.

20 Conveniently, the arms are interconnected by resilient means to maintain them both resiliently in engagement with the picker and in one form the arms embrace the picker on that side of its pivot remote from the needle bed.

25 A modification of the invention comprises the combination with a picker pivoted about two axes transverse to one another of a plunger end-wise movable along one of these axes or in a line parallel therewith and a coupling between the plunger and the outer end of the picker which can transmit thrust to the picker in a line along or parallel with one of the axes and allows resilient movement of the picker around the same axis.

30 Preferably, the picker lever is pivoted about vertical and horizontal axes respectively, the plunger is vertically movable and the coupling transmits the thrust in a vertical direction to the picker and permits resilient movement of the picker around that vertical axis.

Thus according to this invention the coupling between said plunger and the outer end of the picker lever may comprise a pivoted member arranged to transmit thrust from said plunger to said picker in a vertical direction and controlled by resilient means to allow movement of said picker about its vertical axis. The resilient means may be arranged to bring the coupling member (and the outer end of the picker lever) back to normal position after the picker has completed an operation and passed out of contact with the needles.

A preferred form of this invention comprises in a circular knitting machine the combination with a picker lever pivoted about a vertical axis and also about a horizontal axis, of a vertically movable plunger and a coupling between the plunger and the outer end of the picker lever comprising a bar fixed to the plunger at right-angles to its axis and two arms pivoted to the opposite ends of said bar, recessed on their upper inner faces to embrace said picker end in all positions, and a spring connecting said two arms so as to restore them to their normal position when the picker lever has completed an operation.

The picker lever may itself be spring controlled to assist the return of the picker lever to its central or receiving position in relation to the needle cylinder and to assist the picker lever (and associated parts) to return to inoperative position when the plunger is free from axial thrust.

In order that the invention may be more clearly understood a preferred example will now be described in detail with the aid of the accompanying drawing, in which—

Figure 1 is a side elevation of a picker mechanism constructed according to the present invention, and

Figure 2 is an elevation looking from the right in Figure 1.

Like reference numerals indicate like parts in both figures of the drawing.

The picker mechanism is intended to be applied to a circular knitting machine having a moving needle cylinder and a stationary cam box. A bracket 10 fixed to a stationary part of the machine outside the needle cylinder has a vertical cylindrical hole in which can rotate the vertical stem 11 of a support 12 for the picker lever 13. The picker lever is pivoted on a horizontal pin 14 in the support 12. The inner end of the picker lever has a recess for the reception of the needle butts on each side, each recess being formed by a horizontal portion 15 and a vertical wall 16 conveniently of T-form in section. It will be realised quite clearly that the picker lever 13 can move freely in its vertical plane about pin 14 and can also oscillate around the axis of vertical stem 11 so that the picker is movable as heretofore in any direction in its own sphere.

In another cylindrical hole is located a cylindrical portion 17 of a plunger 17, 18 of which the part 18 is formed as a head having a flat face which bears at 19 against a corresponding flat face of bracket 10. The bearing of these two flat faces prevents rotation of the plunger around the axis of the cylindrical portion 17. The object of the plunger is to actuate the picker and in particular to impart vertical movement to the rear or outer end thereof. The plunger is subject to vertical movements at appropriate times by mechanism which forms no part of the present invention but which may conveniently comprise

a lifting cam or lever which engages with the under side 20 of the cylindrical part 17 of the plunger.

On the outer side of the plunger head 18 is fixed by means of screw 32 a horizontal bar 21 projecting a short distance on each side of the axis of plunger 17, 18. At opposite ends of bar 21 there are pivoted, on horizontal pins 22, 23, arms 24 and 25 respectively the function of which is to act jointly as a coupling to the outer end of picker lever 13. These two arms 24 and 25 lie in a vertical plane and their upper ends are notched or cut away at adjacent corners, each notch being formed with one wall that is more or less lengthwise of the arm and another wall that is transverse thereto. The notches are such that in the first place they can overlap as shown clearly in Figure 2 to embrace between them the outer end 26 of the picker 13 and the opposed faces of the arms are rebated so as to overlie one another each with half its thickness as clearly shown in Figure 1. When in engagement with the end 26 of the picker the two arms are conveniently inclined endwise like the arms of letter A as seen best in Figure 2 and a convenient form of notch for the end of each lever is a right-angled recess cut inwardly from the outer end of the arm as shown. The two arms are coupled together by a spring 27 which performs the triple function of (a) holding the notched portions of the arms in contact with the outer end of the picker arm, (b) allowing resilient lateral movement of the end 26 of the picker and of the arms themselves, and (c) restoring the picker end 26 and the arms to their normal mid position, illustrated in the drawings after the picker is freed from the needles.

When the plunger 17, 18 is in its lowest position, the inner end 15, 16 of the picker is raised into an inoperative position; but when plunger 17, 18 is raised this moves upwardly, the outer end 26 of the picker thus lowering its inner end in the vertical direction to a position ready for picking. Lateral movement due to the rotation of the needle cylinder and the engagement of the butts of the needles or needle jacks is accommodated by the form of coupling comprising arms 24, 25 and spring 27 already described.

A fine adjustment for the exact setting of the operative position of the picker may be provided and in the example shown a pointed screw 28 acts by means of its pointed extremity as a stop to engage the lower edge of a hole 29 formed in the plunger part 17. The screw 28 is located in its adjusted position by means of a lock-nut 30.

The picker lever 13 itself is conveniently controlled by resilient means such as a spring or springs 31 compressed between the picker arm and its support 12 on the cylinder side of pin 14. A spring such as 31 assists in returning the picker to its central or receiving position and plunger 17, 18 to its inoperative position, and furthermore it also assists spring 27 in centralising arms 24 and 25 when the plunger is no longer under thrust and the picker itself is free from engagement with the needles or needle jacks.

I claim:

1. In or for a circular knitting machine, the combination of a picker movable about two axes transverse to one another, means which serves to rock the picker about one axis and which comprises two arms inclined towards one another to embrace the picker, resilient means to permit and to control movement of the picker about the

other axis and means to impart movement to the arms which movement is transmitted by the arms to the picker to rock the latter.

2. In or for a circular knitting machine, the combination according to claim 1 in which movement imparted to the inclined arms is such as to rock the picker about an axis that will move its operative end lengthwise of the needles.

3. In or for a circular knitting machine the combination of a picker pivoted about two axes transverse to one another, a plunger movable endwise in a direction lengthwise of one of these axes, a coupling between the plunger and the outer end of the picker comprising a bar fixed to the plunger and at right angles to its axis and two arms which are pivoted to the opposite ends of said bar are recessed at their upper inner faces to embrace the said picker in all positions, and a spring connecting the said two arms to restore them to their normal position after they have been moved therefrom by movement of the picker and means for moving the plunger.

4. In or for a circular knitting machine, the combination of a picker movable about two axes transverse to one another, a member movable in a direction lengthwise of one of these axes, means comprising a resilient coupling between the said member and the picker through which thrust is transmitted to the latter and which will permit resilient movement of the picker around the same axis, and spring means controlling return of the picker to its central or receiving position in relation to the needle cylinder after it has been displaced from that position and is returned to its inoperative position.

5. In or for a circular knitting machine, a device comprising in combination a picker lever pivoted intermediate its ends in a support, a bearing for said support in which the latter is rotatable about an axis at right angles to the pivotal axis of the picker, a plunger endwise movable in a guide in a direction parallel with the axis about which the picker support rotates, a bar secured to and extending on both sides of the plunger at right angles to the axis of the

latter, two arms pivoted at their lower ends at or near the extremities of the bar and convergent upwardly, the said arms having recessed upper extremities which are overlapped to embrace between them the outer extremity of the picker lever, a tension spring interconnecting the two arms at positions between their extremities for the purpose of causing the arms resiliently to embrace the picker end in all positions.

5 6. In or for a circular knitting machine, the subject matter of claim 5 having in addition a compression spring received in the picker support to engage the picker between its pivotal axis and its operative extremity, for the purpose described.

10 7. In or for a circular knitting machine, the combination according to claim 5 in which the plunger is formed with a recess and is combined with an adjustable stop which enters the recess to an adjustable degree to limit movement of the plunger at least in an upward direction.

15 8. In or for a circular knitting machine according to claim 5 and in addition a compression spring received in the picker support to engage the picker between its pivotal axis and its operative extremity, a recess in the plunger and an adjustable stop in the plunger support to enter the recess to an adjustable degree to limit movement of the plunger at least in an upward direction.

20 9. In or for a circular knitting machine, the combination of a picker movable about two axes transverse to one another, a member movable in a direction lengthwise of one of these axes and means comprising a resilient coupling between said member and the picker through which coupling thrust is transmitted to the picker along said line and will permit resilient movement of the picker around the same axis.

25 10. In or for a circular knitting machine, the combination according to claim 9 in which a plunger constitutes the movable member and is movable in an axial direction for the purpose of imparting the requisite movement to the picker.

CARLYLE HERBERT WAINWRIGHT.
